UNITED STATES PATENT OFFICE

166,737

METAL DOOR HOOD

Robert A. Childers and Claud C. Miller, Houston, Tex., assignors to Childers Manufacturing Co., Houston, Tex., a corporation of Texas

Application July 27, 1950, Serial No. 11,427

Term of patent 14 years

(Cl. D21—6)

To all whom it may concern:

Be it known that we, Robert A. Childers and Claud C. Miller, both citizens of the United States and residing at Houston, Texas, have invented a new, original, and ornamental Design for a Metal Door Hood, reference being had to the accompanying drawing, forming part thereof.

In the drawing:

Fig. 1 is a perspective view of a metal door hood showing our new design;

Fig. 2 is a front view thereof;

Fig. 3 is an enlarged fragmentary view, partly in section taken along lines 3—3 of Figs. 1 and 2, representing the corrugated and crimped formation of the front panel and both side portions of the door hood shown more particularly in Fig. 1; and

Fig. 4 is a fragmentary side view on an enlarged scale of a portion of the metal door hood.

The dotted lines shown in Figs 1 and 2 are for illustrative purposes only.

We claim:

The ornamental design for a metal door hood, as shown and described.

ROBERT A. CHILDERS.
CLAUD C. MILLER.
